INCORPORATED, OF NEW YORK, N. Y., A CORPORATION OF NEW YORK.

SYSTEM OF SPACE DISCHARGE DEVICES.

Application filed February 25, 1924. Serial No. 694,864.

This invention relates to systems of space discharge devices and more particularly to an arrangement whereby a plurality of three electrode devices of this type may be connected in parallel.

In systems including parallel connected three electrode discharge devices heretofore proposed, the devices have been arranged in a single row, or at the angles of an irregular geometrical figure. The conductors through which energy is supplied to and from the electrodes of the discharge devices to a load circuit have been connected at one end of the row or at some point on the geometrical figure which is not symmetrically positioned relatively to the leads connecting the electrodes of the several devices to the energy supply conductors. Again, where anti-singing choke coils have been used in the output circuits of the devices, they have in general been connected into each circuit at some point remote from the anode of the device.

When three electrode space discharge devices are used to amplify alternating current, it is well known that, because of distorting action of the devices, current components of frequencies harmonically related to the frequency of the amplified current will be produced in the circuits associated with the devices.

Again, when devices of this type are used as amplifiers, there is a tendency to produce sustained oscillations, or "singing", due to feeding back some of the amplified energy to the input side of the amplifier circuit. The amplified energy may be fed back by any coupling relation between the input and output circuits of the amplifier. A common form of coupling is the internal capacities between the electrodes of the discharge devices. If the tendency to develop sustained oscillations is very marked, it is impossible to realize a high degree of amplification, since the amplifier must be operated to give a smaller amplification than that at which sustained oscillations occur.

In amplifier systems heretofore proposed, as described above, the frequency of the parasitic oscillations produced are harmonically related to the frequency of the energy to be transmitted through the system. They are in general caused by the distorting action of the space discharge devices, the

unequal lengths of the conductors connecting the source of input energy to their control electrodes, and the fact that the anti-singing choke coils are included in the output circuits at points remote from their anodes.

The reason for this resides in the fact that the input conductors possess different values of inductance and capacity which co-operate with the inductances and capacities of the leads between the anode and the choke coils to build up the amplitudes of the harmonically related impulses produced by the devices until they are of sufficient value to produce sustained oscillations at these frequencies. The tendency to produce parasitic oscillations is directly proportional to the lengths of the grid and anode-choke coil leads.

This invention provides an amplifying system, including parallel connected three electrode space discharge devices, in which the production of undesired oscillations is limited to a single frequency, and "anti-singing" choke coils are included in the output circuits of the devices to more efficiently suppress these oscillations than in the systems heretofore proposed.

In accordance with this invention a plurality of parallel-connected three electrode space discharge devices are mounted on a supporting panel in two groups, one group projecting upwardly and the other downwardly from the panel, with the corresponding devices of each group in axial alignment. The control electrodes of the groups of devices are connected in pairs by short leads which are connected to a centrally positioned common busbar. The midpoint of the bus-bar is connected by a conductor to the source supplying energy to the control electrodes, and anti-singing choke coils are mounted on the anode terminal contacts of the devices.

The primary object of this invention is to increase the efficiency of parallel-connected space discharge devices.

Another object is to reduce the tendency of parallel connected space discharge devices to produce sustained oscillations of undesired frequencies.

A further object of the invention is to suppress parasitic impulses at the output terminals of the discharge devices.

A feature of this invention is to provide a system for connecting a plurality of space discharge devices in parallel so that each device supplies the same amount of energy to a load circuit.

5 Another feature is the provision of a symmetrical connection for the control electrodes of a plurality of parallel connected space discharge devices.

10 A further feature is to provide conductive paths of substantially equal lengths for connecting the input supply source to the control electrodes of parallel-connected space discharge devices.

15 A still further feature is the provision of means whereby the necessary auxiliary apparatus may be included in the output circuits of the discharge devices without causing the production of parasitic oscillation.

20 For a complete understanding of the invention and the operation of its various parts, reference should be made to the following description read in conjunction with the attached drawing in which, Figs. 1 and

25 2 show respectively front and side views of the supporting structure for the discharge devices and Fig. 3 illustrates a radio transmitter to which the invention is applied.

In the various figures of the drawings 30 the same reference characters are used to indicate the same parts.

Referring to Figs. 1 and 2 there is shown a frame comprising a vertical panel 1, a base 2, standards 3 and a horizontal panel 35 or mounting plate 4 secured at its inner edge to the panel 1 and at its outer edge to the base 2 by the standards 3.

Space discharge devices 5 are mounted in sockets 6 secured to the upper and lower 40 faces of the panel 4 to constitute two sets 7 and 8.

Each of the sets 7 and 8 comprises six devices arranged in two groups. One group of each set consists of three devices 45 projecting vertically above the panel 4 and a second group of three devices projecting downwardly from the panel 4. The corresponding devices of the two groups are arranged co-axially to form a pair.

50 The two sets of devices are therefore symmetrically positioned relatively to the panel 4 and the space occupied by each set is determined by the number of devices included in it, by the dimensions of the bases 55 6 and by the heights of the devices 5.

The sockets 6 are each provided on one face with a pair of filament contacts 9 and a contact 10 for the impedance control electrode or grid. On the opposite face of the base is an anode contact 11.

60 The corresponding contacts 9 of the axially aligned devices are connected together by leads 12 which are in turn connected to a common conductor 13 leading to one terminal of a source for supplying heating

current to the filaments. The other terminal of the heating current source is connected to the other filament contacts 9 by separate conductors 14.

The contacts 10 for the impedance control electrodes are connected in pairs to a common conductor or busbar 15 lying in a horizontal plane centrally of the contacts 10. The midpoint of the busbar 15 is connected by a conductor 16 to a binding post 17 mounted on the panel 1. The source of input energy is connected to the binding post 17 and to the filament conductor 13.

Mounted on and electrically connected to each of the anode contacts 11, as shown in Fig. 1, is a choke coil 18.

The choke coils 18 are designed to provide a low impedance path of alternating current of the frequency to be amplified by the devices 5, but to impose an impedance 85 adapted to substantially prevent the flow of alternating current components of frequencies harmonically related to that of the amplified current.

The control electrodes of the devices are 90 symmetrically connected by the busbar 15 and conductor 16 to the source supplying input energy. The leads extending from the busbar 15 to the contacts 10 are very short and the lengths of the conductors connecting the control contacts of the different devices to the input source are substantially equal. Thus the impedance of the input circuit for each of the devices will be equal and hence the same voltage will be impressed upon their control electrodes, with the result that the impedance of the space path within each amplifier is the same and 100 amplified currents of the equal amplitudes will be supplied to the load circuit by each 105 of the devices.

By mounting the choke coils directly upon the anode contacts 11 any impulses of undesired frequencies will be suppressed at the output terminal of the devices. These 110 coils should have such impedance that they serve to determine the impedance of the output leads for the energy to be amplified, with the result that any desired length of lead, including the necessary auxiliary apparatus, may be used for supplying energy of desired frequency to the load circuit without causing parasitic oscillations to be produced in the circuits of the system.

As shown in Fig. 1, the output circuit of 120 each of the six parallel connected devices constituting a set may be traced from its contact 11 through the choke coil 18, jack 19, fuse 20 to a common conductor 21 which is connected to a binding post 22 mounted 125 on the panel 1. As is usual the jacks 19 are employed to permit a meter to be included in the output circuit, whereby the current supplied by each device to the common conductor 21 may be measured. The 130

fuses 20 are used to protect the discharge devices against high potentials which may damage or even destroy them.

The system described above has been used 5 in a radio telephone system similar to that shown in Fig. 3, in which a source 24 supplies low power waves of carrier frequency through an amplifier 25 to a set of six parallel connected discharge devices 5 for raising 10 the carrier waves to high power. This set of devices may correspond to that shown at 7 in Fig. 1. The two parallel connected high power devices in this figure are intended to represent a set of six. The output 15 circuit of the amplifier 25 is connected through a coupling transformer 26 to the binding post 17 and thence through the conductor 16 and the common input bus bar 15 to the grids, across the space within the 20 devices to their cathode and back to the transformer 26.

The output circuits of the devices 5 include the choke coils 18 and are connected to the common output conductor 21. The 25 space current circuit may be traced from the positive terminal of the source 27, through high impedance choke coil 28, radio frequency choke coil 30, antenna coupling coil 31, conductor 21 and anti-singing choke coils 30 30 18, to the anodes, across the space within the devices to their filaments and back to the negative terminal of the source 27. A condenser 32 provides a low impedance path 35 for amplified alternating current in shunt to the source 27.

Low power speech currents are supplied 40 by the microphone circuit 33 through an amplifier 34 to the parallel connected set of amplifiers 8, herein represented by two devices.

The output circuit of the amplifier 34 is coupled by a transformer 35 to the input of circuit of the parallel connected discharge devices comprising the set 8. One terminal 45 of the secondary of the transformer 35 is connected to the cathode of the discharge devices. The other terminal is connected to the binding post 17 which is in turn connected through the conductor 16 and common busbar 15 to the control electrodes of the 50 devices.

Space current is supplied to the devices of set 8 from the positive terminal of the source 27, through the impedance choke coil 36, common conductor 21, anti-singing choke coils 18 to the anodes, across the space within the devices to the cathodes and back to the negative terminal of the source 27.

The negative terminal of the source 27 is 55 grounded at 37.

The high power speech currents flow 60 through the condenser 38 to modulate the space current supplied to the high power devices comprising the set 7, whereby high 65 frequency waves having their amplitudes

modulated in accordance with speech are supplied through the coil 31 inductively associated with the coil 39, included in the antenna circuit, for transmission to a distant station.

Although a set consisting of six devices has been described above it will be apparent that by connecting the control electrodes of the discharge devices to a common busbar having its midpoint connected to the source supplying input energy thereto and mounting an anti-singing choke coil on each anode contact, the principles of this invention may be applied to a set comprising an odd or even 70 number of devices.

From the preceding description it will be seen that this invention provides a system, including a plurality of parallel connected space discharge devices, in which "singing" 75 can occur at but one frequency, the impedances of the discharge path of the different devices are equal and the maximum effect of the anti-singing choke coils in suppressing 80 undesired oscillation is obtained.

While a certain specific arrangement of 90 the apparatus and its application to a particular use have been described for the purpose of clearly and completely disclosing the nature of the invention, it is to be understood 95 that this invention is not limited to the specific features or use disclosed, but only by the scope of the attached claims.

What is claimed is:

1. Means for supporting space discharge devices comprising a horizontal panel and 100 sockets for said devices secured to the opposite faces of said panel said oppositely disposed sockets being arranged in axial alignment.

2. Means for supporting a plurality of 105 space discharge devices each having a plurality of electrodes, comprising a panel, sockets for said devices secured to the opposite faces of said panel, said sockets being each provided with contacts corresponding 110 to said electrodes, a conductor lying in a plane centrally of said oppositely disposed sockets, means for connecting the contacts of corresponding electrodes of said devices to said conductor, and means for connecting the midpoint of said conductor to a binding post.

3. Means for supporting a plurality of 120 space discharge devices each having a plurality of electrodes, comprising a horizontal panel, sockets for said devices secured to the opposite faces of said panel, said sockets being arranged in axial alignment and each being provided with contacts corresponding 125 to said electrodes, a conductor symmetrically located with respect to said sockets, and means for connecting corresponding contacts of said sockets to said conductor.

4. An electrical system comprising a plurality of three electrode space discharge de- 130

vices, external circuits for said devices, means for connecting one of said external circuits symmetrically to the corresponding electrodes of said devices, and parasitic oscillation suppressing means included in the other external circuit closely adjacent the connection of other corresponding electrodes of said devices.

5. An electrical system comprising a plurality of space discharge devices, each having a cathode, an anode and an impedance control electrode; said devices having cathode-control electrode circuits which are of equal impedances, a contact for each of said 10 anodes and cathode-anode circuits, and means for suppressing undesired oscillations directly connected to each of said anode contacts.

6. An electrical system comprising a plurality of space discharge devices, each having a cathode, an anode and an impedance 15

control electrode, said devices having cathode-control electrode circuits which are of equal impedances, a contact for each of said anodes, and "anti-singing" choke coils 20 mounted upon and connected to each of said anode contacts.

7. An electrical system comprising a plurality of three electrode space discharge devices, said devices being coupled to external 25 circuits by input and output circuits adapted to permit "singing" at one undesired frequency only, and means, included in said output circuit closely adjacent the point of origin of impulses of undesired frequency, 30 for reducing said impulses to negligible amplitudes.

In witness whereof I hereunto subscribe my name this 23rd day of February A. D., 1924.

ERNEST J. STERBA.
